*Primary Examiner—Stella Reid**Assistant Examiner—I Simmons**Attorney, Agent, or Firm—Keith J. McWha*[57] **CLAIM**

The ornamental design for a specimen collection container, as shown and described.

DESCRIPTION

FIG. 1 is a top left side perspective view of a specimen collection container, showing our design;

FIG. 2 is a left-side view of the container of FIG. 1, the right-side view being a mirror image thereof;

FIG. 3 is a top-plan view of the container of FIG. 1;

FIG. 4 is a front view of the container of FIG. 1;

FIG. 5 is a rear view of the container of FIG. 1; and,

FIG. 6 is a bottom-plan view of the container of FIG. 1.
